FIRE-EXTINGUISHING APPARATUS.

1,143,169.

Specification of Letters Patent. Patented June 15, 1915.

Application filed July 16, 1913. Serial No. 779,407.

To all whom it may concern:

Be it known that I, EDWARD R. BRODTON, a citizen of the United States, residing at Washington, in the District of Columbia, have invented certain new and useful Improvements in Fire-Extinguishing Apparatus, of which the following is a specification.

This invention relates to fire extinguishing apparatus in which the extinguishing fluid, whether a chemical or water, is automatically discharged upon the fire by the opening of sprinkler heads applied to the pipes when a fire-produced temperature exists.

The object is to provide an apparatus of high efficiency which will be certain to operate under the conditions intended and will not accidentally operate.

20 In its best form the invention contemplates the use of a fire extinguishing fluid supplied through pipes that run to the various parts of the structure to be protected, a building, or a ship, for example, and such 25 fluid in the pipes is under an initial pressure, and an expelling pressure is supplied by a gas generated in a suitable tank, as by mixture of sulfuric acid and bicarbonate of soda, this mixture being automatically effected.

In the drawings—Figure 1 is a diagrammatic view of a form of my invention applied to the rooms of a building; Fig. 2 is a section of the portion of the apparatus; 35 Fig. 3 is a detail view of an alarm or signal device that may be used; Figs. 4 and 5 are, respectively, detail views in end and side elevation of the mechanism that controls the communication between the sulfuric acid and the soda solution holders; Fig. 6 is a detail view showing the mechanism by which the system is automatically thrown out of operation; Fig. 7 is a detail view in section of a diaphragm form of operating device.

45 In this system, a tank *b* is provided, which tank is adapted to contain a fire extinguishing liquid. The liquid contained in this tank may consist of pyrene or like chemical, which will be absolutely harmless to any 50 materials contained in the rooms in which the system is located. Leading from the bottom of the tank *b* is a main pipe *c*, which pipe is provided with a plurality of branch pipes *20*, these branch pipes being connected

at one end of the main pipe *c* and at the 55 opposite end to a pipe *c*⁵. Located between the extremities of the pipes *20* are a plurality of thermal valves *2*, these valves having communication with the interior of the pipe *20*, and being adapted to discharge the liquid 60 contained therein when the temperature of the room rises to a predetermined point, this being caused by the presence of fire in the room.

Leading from the top of the tank *b* is a 65 pipe *c*², said pipe having a horizontal bend within which is placed a suitable check valve of the bypass type and which is designated by the letter *l*. This pipe has a vertical extension *c*³, upon the upper extremity of 70 which is a glass air dome *s*. Communicating with the vertical extension *c*³ of the pipe *c*² is a pipe *p* having a valve *p*', which pipe affords means by which the liquid is introduced into the tank *b*. Carried by the pipe 75 *p* is a tubular member *r* provided with a valve *q*, the purpose of which will be hereinafter set forth. Connected to the pipe *c* is a branch pipe *c*' which extends horizontally therefrom and has a vertical extension 80 *c*⁶ and a second horizontal extension *c*⁷ which communicates with the second liquid containing tank *a*, the liquid contained in this tank *a* being soda solution.

As disclosed in Fig. 2, a cylinder *e*' communicates with the vertical extension *c*⁶ of the pipe *c*', this cylinder being provided with a piston *25*' whose end *26*' is connected to a vertical pivot member *27*', pivoted at 85 *28*'. The above described mechanism is inclosed in a casing *G*. Also inclosed in the casing and pivoted at *29*' is a member *30*', said member being provided with a downwardly extending hook portion *31*', which hook portion engages in an eye *32*' in a 90 weighted lever *33*', more clearly shown in Fig. 7.

Connected to the soda solution tank *a* by means of a pipe *j* is a tank *d*, which tank is adapted to contain sulfuric or other acid 10 capable of generating a fire extinguishing gas, this tank being filled with acid through the aperture *19* in the top thereof. Also communicating with the soda solution tank and with the top of the acid containing receptacle at a point above the level of the acid contained therein is a pipe *i* controlled by a check valve *f* and a turning plug *h*. This

sliding valve k also controls the passage of acid through the pipe j . The submerged extremity of the pipe j is perforated as at 25. Connected with the pipe c' at one end and with a vertical extension c^{10} of the tank b at the other end is a pipe 40, this pipe being controlled by a valve 28. A branch a' connects the pipe c' with the space between the level of the soda solution in the tank a , and this passage is controlled by a valve a^2 .

The system, as at present described, is filled with the aforementioned chemical such as pyrene, the filling of the system being indicated by the level of the chemical in the vertical extension r carried by the pipe p . Since the level of the chemical is visible in the vertical extension r , the valve q is cut off to prevent the overflowing of the liquid contained in the system. By further forcing of liquid into the system all of the air remaining in the air dome s is compressed therein, which pressure is used in the forcing of the liquid from the system in case of operation of the thermal valves 2.

Pyrene, or a chemical of like nature, is particularly adapted to a fire extinguishing system for the reason that it would not be destructible to any materials contained in the room or compartment with which it might come in contact, and furthermore it contains elements which not only prevent its freezing and disabling the system, but also will not to any great extent affect the pipes of the system regardless of the material from which it might be made.

The pressure of the chemical in the pipes c , c^5 , 20 and c' will be sufficient to keep the piston 25' to its seat, and thus prevent any operation of the device.

Supposing a fire to break out in any one of the compartments, in which is located one of the pipes 20 which carry the thermal valves 2, the increase in temperature of said compartment will cause the valves to fuse, thus opening them and permitting a discharge of the chemical contained in the system and in the tank b . Upon the discharge of this chemical, the reduced pressure on the piston 25 permits the spring 35' to operate the same, thus rocking the member 27' on its pivot 28' to the position shown in full lines in Fig. 2. Such a movement of the member 27' releases the member 30' which swings upon its pivot 29' and disengages its hooked lower extremity from the eye 32' in the weighted lever, thus releasing the same and upon the release thereof said weighted lever swings on its pivot to operate the valve k and move the same to the position shown in Fig. 2. This permits of a flow of the sulfuric or other acid contained in the tank d through the pipe j and through the perforations 25, thus thoroughly mixing the same with the soda solution contained in the tank a , which generates a gas that rises, and by means of a passage a'

passes out through the pipe c' , valve 28, and pipe 40 to the tank b , wherein it acts to force the chemical contained in said tank through the system to the opened valves 2.

By reference to Fig. 6 it will be seen that means is provided to automatically cut off any flow of soda solution from the tank a to the tank b , if desired, this mechanism consisting of a dome-shaped member o^{10} , within which is vertically movable a rod or the like o^{11} , which rod has a screw threaded upper extremity which carries a thumb o^{13} . Mounted on this rod is a valve member o^{12} adapted to engage the seat o^{25} and shut off any flow of soda solution into the tank b . Connected near the bottom of this rod is a float o^{26} , which is submerged in the liquid contained in tank b , and it will be seen that so long as this tank contains any liquid, the valve o^{12} will remain unseated. However, upon draining of the tank b , the float falls, thus permitting the valve to seat. If the thumb nut o^{13} be adjusted near the center of the threaded portion of the rod o^{11} , it will upon falling of the float engage the outer face of the upper wall of the casing o^{10} thus preventing the valve from seating.

Referring to Fig. 2, it will be seen that as the gas generated in the tank a increases, it will force the soda solution from the tank a through the bypass i opening the check valve f and entering the tank d above the level of the acid contained therein. This increase of pressure in the soda solution tank causes the soda solution contained therein to back up into the acid receptacle, and when the pressure in the acid receptacle and soda solution tank equalizes, a further flow of the acid into the soda solution tank takes place. As the chemical in the tank d is forced into the soda solution tank, the pressure in the tank d is decreased, while the pressure in the soda solution tank a , owing to the increased amount of chemical being forced thereinto, has increased. This increase of pressure in the tank a causes a repetition of the aforementioned operation, thus charging the chemical tank d with a portion of the soda solution contained in the tank a in order that the chemical in the tank d may be forced against the increase of pressure in the tank a .

As will be seen in Fig. 2, an extension z' of the pipe c' extends down into the soda solution tank a , this pipe being provided with a valve a^2 of the three-way type, which valve may be turned so as to shut off communication of the pipe c' with the bypass a' and when this valve a^2 is in this position the gas generated in the soda solution tank a will force the soda solution contained therein out through the pipe z' , pipe c' , through the cock 28, pipe 40 and to the tank b . It is the object of this construction to use the soda solution to force the

chemical from the tank *b* in lieu of the gas generated in the soda solution tank *a*, if desired.

Referring to Fig. 6, it will be seen that in lieu of the spring pressed piston 25', a diaphragm *w*⁹ can be used, the edges of this diaphragm being secured between the meeting faces of a casing *x*⁸, and having the piston rod connected at its central point as shown at *w*⁸. It will be seen that if the pressure is decreased upon the right hand side of the diaphragm the spring 35' will move the rod to trip the weighted lever.

From the foregoing it will be seen that I have devised a system in which provision is made for the extinguishing of fire by means of a fluid chemical, and for a continuous operation by soda solution should the fluid chemical be insufficient to completely extinguish the fire.

Branching from the pipe *c*' is a casing *w*⁶ which carries a piston similar to the piston 25', this piston operating a latch *w*⁵ similar to the latch 30', which latch *w*⁵ holds the weighted lever *w*³ in a position to maintain the valve *w*² closed. However, after the complete exhaustion of the liquid chemical contained in the tank *b* and the gas generated in the soda solution tank *a*, a reduction of pressure in the system will cause the operation of the last mentioned latch operating means to drop the weighted lever *w*³, thus opening the valve *w*² which is located in the water main and permit a flow of water through the pipe *w*', tank *a*, pipe *c*' and the three-way cock 28 being set to communicate with the pipe 40 it passes through the pipe 40, tank *b*, pipe *c*" and *c*' to the pipe *c* and from thence to the pipes 20 where it is discharged through the open valves 2, the three-way cock *w*" be set to communicate with the pipes *c*', *c*" and cylinder *w*⁶. The course of the water, however, may be changed to flow through the pipe *c*', *c*' to the pipe *c* by the setting of the cock 28. This, however, will be unnecessary in most cases, since the tanks *a* and *b* will be of a capacity sufficient to extinguish a fire in most cases. If, for any reason, however, the generation of gas in the soda solution tank *a* should be prevented, such a condition would not prevent the flow of water through the pipe *w*', through tank *a*, and from thence through the rest of the system, but would take place just the same upon the reduction of pressure in the system, and the operation of the latch releasing member *w*⁶.

Located in each of the extensions 20, and near their junction with the main pipe *c*, is a valve *y*, this valve being maintained normally in its opened position to permit of a free flow of the fire extinguishing liquid therethrough. The purpose of this valve is as follows: A fire having broken out in the compartment or room, and the system set in

operation, the chemical is discharged from the thermal nozzles 2, as before stated, but when the fire in said compartment has become extinguished, a person entering the room may close the system, or throw the same out of operation, merely by closing the aforementioned valve *y*, which valve is maintained in its closed position until new thermal sprinkle heads 2 can be substituted for the ones which were fused by the presence of fire in said compartment, whereupon the valve is again opened and the pipe 20 is permitted to fill with the fire extinguishing chemical.

Located adjacent the aforementioned valves *y* in each of the pipes or branches 20 is a check valve *z*, the purpose of which is as follows: These check valves *z* permit the passage of the fire extinguishing chemical through them in one direction only, and it will, therefore, be seen that upon the operation of the thermal nozzles 2 in any one of the branches 20, these check valves *z* provide the means by which the other branches 20 in adjoining compartments or rooms are prevented from draining of the fire extinguishing chemical contained therein, and all communication between these inoperative branches 20 is cut off from said branch 20 which may be in operation.

For the purpose of draining the branch pipes 20 of the system, valves 17 in the branches 20 and valves 5 in the pipe *c*' are provided, which valves when opened will permit of a passage of fluid contained in the pipes 20 out through the nozzle 4, as shown in Fig. 1. Since the valves *z* are check valves operating in one direction only, the provision of the valves 17 and 5 is necessary since the fluid would not pass backwardly through the valves *z*.

Connected to the pipe *c* is a valve 11, and to this valve 11 is connected a hose 22 which is suitably supported by a hook 13. Connected to the pipe *c* is a suitable catch or the like 12, which also aids in the supporting of the hose. Upon the removal of the hose from its hook 13 and the spring catch 12, the valve 11 is automatically opened, this being due to an engagement of the hose with the valve lever, and the fire extinguishing chemical will immediately begin to pass through the aforementioned hose 22. This part of my system may be put in use provided a fire is discovered in any of the rooms before the automatic nozzles 2 have had time to set the system into operation.

Branching off from the pipe 20 and starting at a point between the valve *y* and the check valve *z* is a pipe 1, which pipe may lead to a compartment on the same floor with the pipe 20. This pipe or extension 1 is provided with a check valve 14 similar to the check valves *z* before mentioned, and it is the purpose of this check valve 14 to pre-

vent the discharge of fire extinguishing chemical from the pipe 1 should a fire occur which would affect the automatic nozzles carried by the pipe 1.

- 5 Connected to the pipe p is an indicator 24, which indicator, by suitable means of wiring, is connected to an audible signal v and a visual signal v' . It is the purpose of this indicator to announce by the operation of 10 the said audible and visual signals any reduction of pressure in the system behind the valve l which may be due to leakage or other causes. A similar indicator u is connected with the tank b and by means of 15 suitable wiring is connected to audible and visual signals to indicate the fall or rise of pressure in the tank b . This fall or rise of pressure in the tank b would be due only to an accidental leakage of acid contained 20 in the tank d , which acid would pass into the soda solution tank a , thus generating a gas. By this arrangement it will be seen that I have provided means for indicating any reduction of pressure in the system 25 which causes the device to be inoperative.

Connected to the main pipe c of the system is a casing m within which casing is a spring pressed piston, which upon the reduction of pressure in the system moves the 30 member 15 connected thereto to operate the bell n and a visual signal o , this being shown in Fig. 1. This signal not only operates to indicate the reduction of pressure in the system due to leakage or the like, but will 35 also indicate the presence of fire and the operation of the system, since a reduction of pressure cannot be caused therein by the operation of the system or a leakage therein.

Located at different points on the pipe c' 40 are similar casings e which also carry spring pressed pistons which are adapted to move upon a reduction of pressure in the system to operate suitable signals 2^a , 2^b , and 2^c , it being the object of these signals to tell in 45 just which compartment the fire is located by the number of taps given thereby, which is accomplished by suitable mechanism provided in each bell.

In the same circuit with the audible signals 2^a , 2^b , 2^c , and the audible signals v and visual signals v' is a siren or the like W , which is also intended to indicate the presence of fire upon the operation of any of the signals 2^a , 2^b , 2^c .

55 Referring again to Fig. 2, it will be seen that pipe c' is provided with a check valve c'' , which check valve is held to its seat by means of the liquid contained in the tank b , and which is forced from its seat w on the 60 generation of gas in the top of the soda solution tank a , which gas will not be generated, however, until sufficient of the chemical has passed out of the system to reduce the pressure on the piston $25'$, which reduction of 65 pressure, as before stated, will set into op-

eration the mechanism which discharges the acid contained in tank d into the body of soda solution contained in tank a .

I will now describe another method of operation of my system in which I use air 70 pressure in lieu of a generating gas to force the chemical from the tank b . In this method of operation I dispense with the chemical tank d and the operating mechanism disclosed in Fig. 2, and adjust the tension of 75 the spring controlled piston in the casing w^6 so that upon the reduction of pressure in the system the latch w^5 is released, thus opening the water valve w^2 . This flow of water through pipe w' causes the compression 80 of air in the tank a and said air under pressure is forced out through the pipes a' , c' , through the valve 28 and the pipe 40 to the chemical containing tank b . From this it will be seen that I can dispense with the 85 soda solution in the tank a , the sulfuric acid in the tank d and the mechanism for causing a precipitation of sulfuric acid in the tank d into the tank a for the purpose 90 of generating a gas.

What I claim is:

1. A fire extinguishing system comprising in combination a source of supply of an extinguishing fluid, a discharge pipe leading therefrom that has an outlet, the contents 95 of said pipe being kept under a pressure tending to cause the efflux thereof from the pipe, means that normally hold the pipe outlet closed against such efflux, holders or receptacles for separately holding chemicals 100 which when brought together generate a pressure-producing gas, a connection between one of said receptacles and the source of supply of extinguishing fluid for transmitting the gas pressure to the latter, a device 105 for controlling the commingling of the chemical contents of the receptacles, and means establishing communication between said discharge pipe and said device to cause the operation of said device to cause the 110 commingling of the chemical contents of the receptacles, when the pressure in the discharge pipe is reduced by the opening of its outlet.

2. A fire extinguishing system comprising in combination a source of supply of an extinguishing fluid, a discharge pipe leading therefrom that has an outlet, the contents of said pipe being kept under a pressure tending to cause the efflux thereof from the pipe, means that normally hold the pipe outlet closed against such efflux, a pair of tanks for separately holding chemicals which when brought together generate a pressure-producing gas, means for establishing communication between said tanks, a pipe connecting one of said tanks and the source of supply of extinguishing fluid for transmitting the gas pressure to the latter, a device 115 controlling the communication between the pair 120 of tanks.

of tanks, and means establishing communication between said discharge pipe and said device to cause the operation of said device to open communication between the pair of tanks when the pressure in the discharge pipe is reduced by the opening of its outlet.

3. A fire extinguishing system comprising in combination a holder for a fire extinguishing fluid, a discharge pipe leading therefrom that has an outlet, the contents of said pipe being kept under a pressure tending to cause the efflux thereof from the pipe, means that normally hold the pipe outlet closed against such efflux, a pair of tanks for separately holding chemicals which when brought together generate a pressure-producing gas, a pipe leading from one of said tanks and branching to connect with said holder and with said discharge pipe respectively, means for establishing communication between said pair of tanks, a device controlling such communication and itself exposed to the pressure within the discharge pipe and acting upon reduction of such pressure to open the communication between the two tanks.

4. A fire extinguishing system comprising in combination a source of supply of an extinguishing fluid, a discharge pipe leading therefrom that has an outlet, the contents of said pipe being kept under a pressure tending to cause the efflux thereof from the pipe, means that normally hold the pipe outlet closed against such efflux, a pressure tank, a pipe connecting the same and the source of supply of fire extinguishing fluid, means for causing the production of pressure in said tank, including a normally closed pipe that runs to said tank, and means to open said normally closed pipe acting upon reduction of such pressure in the discharge pipe.

5. A fire extinguishing system comprising in combination a source of supply of an extinguishing fluid, a discharge pipe leading therefrom that has an outlet, the contents of said pipe being kept under a pressure tending to cause the efflux thereof from the pipe, means that normally hold the pipe outlet closed against such efflux, a pressure tank, a pipe connecting the same and the source of supply of fire extinguishing fluid, means for causing the production of pressure in said tank, including a normally closed pipe that runs to said tank, and means to open said normally closed pipe including a device exposed to the pressure within the discharge pipe, and acting upon reduction of such pressure in the discharge pipe.

6. A fire extinguishing system comprising in combination a source of supply of an extinguishing fluid, a discharge pipe leading therefrom that has an outlet, the contents of said pipe being kept under a pressure tending to cause the efflux thereof from the pipe, means that normally hold the pipe out-

let closed against such efflux, a pressure tank, a pipe connecting the same and the source of supply of fire extinguishing fluid, normally inactive means for causing the production of pressure in said tank, and a device that renders said pressure-producing means active that is exposed to the pressure within the discharge pipe, and acts on reduction of such pressure in the discharge pipe upon the opening of its outlet.

7. A fire extinguishing system comprising in combination a holder for extinguishing fluid, a discharge pipe leading therefrom that has an outlet, means for subjecting the fluid in the holder and pipe to a pressure that causes the fluid to tend to efflux from the pipe outlet, means normally holding the outlet closed, a pressure tank communicating with said fluid holder, normally inactive means for causing the production of pressure in said tank, and a device that renders said pressure producing means active that is exposed to the pressure within the discharge pipe, and acts on reduction of such pressure in the discharge pipe upon the opening of its outlet.

8. A fire extinguishing system comprising in combination, a fire extinguishing chemical tank, a discharge pipe leading therefrom, a plurality of discharge pipes branching off from said discharge pipe, a soda solution tank, a pipe communicating the soda solution tank with the chemical tank, a pipe connecting said pipe with the first-mentioned discharge pipe, an acid receptacle adjacent the soda solution tank, and means carried by the last-mentioned pipe adapted to discharge the acid into the soda solution tank upon reduction of pressure in said last-mentioned pipe for the purpose of generating a gas to force the chemical from the chemical containing tank.

9. A fire extinguishing system comprising in combination, a fire extinguishing chemical tank, a discharge pipe leading therefrom, a plurality of discharge pipes branching from the first-mentioned discharge pipe, a soda solution tank communicating with the fire extinguishing chemical tank, an acid receptacle adjacent to the soda solution tank, a water supply connected to said soda solution tank, means upon reduction of pressure in the system for precipitating the acid in said acid receptacle into the soda solution tank, and means upon a further reduction of pressure operating to communicate the water supply with the soda solution tank, as and for the purpose set forth.

10. A fire extinguishing system comprising in combination, a fire extinguishing chemical tank, a main discharge pipe leading therefrom, a plurality of discharge pipes branching from the first-mentioned discharge pipe, a soda solution tank, a pipe connecting the soda solution tank with the

main discharge pipe, a third pipe connecting said last-mentioned pipe with the fire extinguishing chemical tank, an acid receptacle adjacent the soda solution tank, a water main connected to said soda solution tank, means operating upon reduction of pressure in the system to precipitate the acid contained in the acid receptacle into the soda solution tank for generating a gas to expel the fire extinguishing chemical from the first-mentioned tank, and means operated upon further reduction of pressure in the system to communicate the water main with the soda-solution tank for the purpose of forcing the soda solution from said tank through the system.

11. A fire extinguishing system comprising in combination, a fire extinguishing chemical tank, a discharge pipe leading

therefrom, a soda solution tank, a pipe communicating said soda solution tank with the discharge pipe before mentioned, a branch pipe connecting said last-mentioned pipe with the fire extinguishing chemical tank, an acid receptacle adjacent the soda solution tank, and means operated upon a reduction of pressure in the system for discharging the acid in said acid receptacle into the soda solution tank to generate a gas for forcing the fire extinguishing chemical from said tank, substantially as described. 20 25 30
